UNITED STATES PATENT OFFICE.

EDWARD N. DICKERSON, OF NEW YORK, N. Y.

PROCESS OF BURNING ACETYLENE GAS.

SPECIFICATION forming part of Letters Patent No. 602,833, dated April 26, 1898.

Application filed December 31, 1895. Serial No. 573,884. (No specimens.)

To all whom it may concern:

Be it known that I, EDWARD N. DICKERSON, of No. 253 Broadway, in the city, county, and State of New York, have invented a new and useful Improvement in Processes of and Apparatus for Burning Acetylene Gas, of which the following is a full, true, and exact description, reference being had to the accompanying drawings.

In the burning of pure acetylene gas in ordinary burners a serious difficulty has been encountered, arising from the fact that an ordinary burner—say of one-foot capacity—while burning properly for a short time, after, say, three or more hours of burning deposits carbon on the delivery and gradually chokes the burner. Many different forms of burners have been used in the effort to avoid this deposit. I have discovered that this deposit can be prevented by superheating the gas before its arrival at the point of combustion. This is not accomplished in an ordinary burner, and, in fact, the burners now in use for this purpose are especially adapted to cool the gas, since they consist of metal casings which conduct away readily the heat of the flame, so that the point of delivery of the gas is not sufficiently hot to prevent the deposit of carbon. This deposition can be prevented in two ways, either by forming a burner in such a way as that the gas itself is sufficiently superheated before it arrives at the point of combustion or by carrying the gas before its delivery to the burner through a superheating device.

The apparatus for carrying my processes into effect are shown in the accompanying drawings, in which—

Figure 1 represents a vertical cross-section of my improved burner adapted to carry my process into effect, and Fig. 2 a modification showing a superheating device.

In Fig. 1, A represents a metallic burner, preferably of the union-jet variety, having comparatively small gas-openings therethrough and being preferably of metal. This metallic burner is supported in the heat-insulating collar B, which may be made of porcelain or similar insulating material, the collar B resting in the ordinary burner-column C. The result of this arrangement is that the metal portion A becomes hot and the heat is retained therein, not escaping past the insulator B. The acetylene gas is therefore

heated in its upward passage and will burn 55 at the burner-tip without depositing carbon.

The temperature to which the gas may be heated varies within considerable limits; but a temperature of from 300° to 350° Fahrenheit produces satisfactory results. Of course the 60 temperature must not be so great as to cause the decomposition of the acetylene.

In the form shown in Fig. 2, A is a burner, which may be of any known suitable variety. It is supported in the socket B, resting in the 65 column C. The socket B is preferably, but not necessarily, of insulating material. The column C is provided with the delivery-pipe D, which passes up into proximity to the flame and then delivers into the socket B and 70 thence to the burner. In this way the acetylene gas is superheated before its delivery.

It has been generally believed that the deposit of carbon was due to the too hot condition of the gas at the point of delivery, since 75 acetylene gas decomposes at a red heat, depositing carbon. As a matter of fact, however, the difficulties from deposited carbon are due, as I have discovered, to an opposite condition—namely, the too low temperature of the 80 escaping acetylene gas. By means of this superheating device a very serious difficulty is overcome.

I am aware that regenerative gas-burners of the general Siemens type are old; but those 85 burners are constructed for the purpose of giving an increased light, whereas by my process there is no material difference in the illumination; but the difficulty existing in the previous processes is overcome by the discovery 90 of a principle which seems to be contrary to the generally-accepted theories on this subject.

What I claim as my invention, and desire to secure by Letters Patent, is—

The process of burning acetylene gas, which consists in superheating the same, before its delivery at the point of combustion, to a suitable temperature substantially as specified to prevent the deposition of carbon at the burner, 100 substantially as described.

In testimony whereof I have signed my name to this specification in the presence of two subscribing witnesses.

E. N. DICKERSON.
